His Atty.

UNITED STATES PATENT OFFICE.

JAMES A. WALKER, OF GENESEE, PENNSYLVANIA.

NECK-YOKE.

1,211,795.

Specification of Letters Patent.

Patented Jan. 9, 1917.

Application filed March 14, 1916. Serial No. 84,063.

To all whom it may concern:

Be it known that I, JAMES A. WALKER, a citizen of the United States, and resident of Genesee, county of Potter, State of Pennsylvania, have invented an Improvement in Neck-Yokes, of which the following description, in connection with the accompanying drawings, is a specification, like characters on the drawings representing like parts in each of the several views.

This invention relates to neck yokes used in harnessing horses or other animals to vehicles.

A prime object of the invention is to provide a neck yoke of exceptionally strong, yet light and simple construction, capable of being cheaply produced, and wherein the wooden bar of the neck yoke may be made relatively light and yet by my improved reinforcing means be sufficiently strong for all requirements. To this end I provide an improved construction and arrangement of reinforcing truss rods extending from the ends of the neck yoke bar and connected to a central joining member preferably in loop form and associated with the holding means for the ring that receives the vehicle pole or tongue.

The invention will be better understood from the following description taken in connection with the accompanying drawings and will be thereafter pointed out in the appended claims.

Referring to the drawings Figure 1 is a front elevation showing a neck yoke constructed in accordance with my invention; Fig. 2 is a central transverse section thereof on line 2-2 of Fig. 1; Fig. 3 is a bottom plan view showing the central portion of the neck yoke with the ends of the truss rods and the central rings removed; Fig. 4 is a bottom plan view showing one element of the invention in modified form; and Fig. 5 is an edge elevation of the element shown in Fig. 4.

The neck yoke bar indicated at 10 may be of usual form preferably tapering somewhat toward its ends from its central portion. This yoke bar has its ends equipped with stout metallic end caps 11, 11 and underneath is equipped with eyes 12 to receive and hold in place the hame strap rings 13. Through the central portion of the yoke bar, are passed transversely spaced apart eye-bolts

14, 15 having eyes 16 at the lower ends 55 thereof through which are passed the small rings 17 that engage and hold in depending relation the large ring 18 that receives the pole or tongue of the vehicle. The upper ends of these bolts are threaded to receive 60 clamp nuts 19 and a metallic reinforce and clamp plate washer member 20 is preferably provided to be interposed between these nuts and the wood of the bar to provide an extended clamping surface thereon. In accordance with my invention a stout rod 21 65 is fashioned to an elongated loop form with parallel sides 21^a, 21^b, spaced apart to receive between them the bolts 14, 15 and adapted to be engaged by enlarged washers 70 22 interposed between said loop and the eyes 16; the provision of these washers, however, being merely illustrative and intended to typify any suitable means for clamping said loop against the bar and between it and 75 the eyes 16. The end portions of the loop 21 are outturned from the bar at some little angle as indicated at 23. To these outturned ends 23 are secured the inner ends of truss rods 24 in any suitable way, though I preferably bend the ends of these truss rods 80 closely around the ends of the loop as indicated at 25. The outer ends of these truss rods are bent inward, to pass preferably through passages provided therefor in the 85 end portions of the bar as indicated at 26, and their extremities pass centrally through the end caps 11 having threaded thereon nuts 27 adapted on being set up to draw the truss rods taut and obtain the proper tension 90 thereon. It will be noted that by thus turning outward the ends of the loop member 21 which is preferably formed of stout and strong rod stock, the inner ends of the truss rods 24 are spaced some little distance 95 from the bar 10 and thus best adapted to serve their function of stiffening and strengthening the yoke bar construction. It will be further noted that the elongated rod 100 loop 21 having its central portion directly engaged with the body of the bar and held clamped thereto by the transverse bolts 14, 15 serves to coöperate with the top reinforce plate 20 to strengthen the central portion of the neck yoke, the tension action of the truss rods 24 serving to hold this loop rod member 105 more closely assembled against the body of the bar 10; the loop rod member 21 thus

serving the combined function of a reinforce member to coöperate with the bolts 14, 15 and the member 20 for strengthening the central portion of the bar, and also serving 5 as an attaching means for the inner ends of the truss rods 24 adapted to space them outwardly from the bar to the extent requisite for most serviceable operation.

Instead of having the member 21 formed 10 as an elongated loop as already described, it may be formed of a flat piece of iron as seen at 210 with spaced apart holes 211 therethrough to receive the bolts 14, 15 and with outturned ends 212 which may be apertured to receive the ends of the truss rods 24; in this form of the invention these truss rods 15 may be welded to the outturned ends of the bar 210 if desired.

While I have herein described my invention 20 as for use as a neck yoke, it will be understood that it is also serviceable for other analogous uses such as a breast yoke or the like. I therefore desire the foregoing descriptive statement in this as well as other 25 respects to be considered as illustrative and not restrictive. Further in general I do not desire to be limited to the precise structural details herein exhibited as the invention may be embodied in other specific forms 30 without departing from the spirit or essential attributes thereof, and I therefore refer to the appended claims rather than to the foregoing description to indicate the scope of the invention.

Having described my invention, what I

claim as new and desire to secure by Letters Patent is:

1. A neck yoke or the like comprising a bar having spaced apart clamp bolts extending transversely through the central portion 40 thereof, an elongated member having its intermediate portion clamped by said bolts to said bar to serve as a reinforcement therefor and having its extremities outturned substantially from the surface of the bar, 45 and truss members having their inner ends secured to the outturned ends of said member and having their outer ends secured at the outer ends of said bar.

2. A neck yoke or the like comprising a 50 bar, spaced apart eye bolts passed through the central portion thereof, intermediate rings passed through the eyes of said bolts, a pole receiving ring held by said intermediate bolts with a capability of limited lateral 55 and endwise movement, an elongated member having its intermediate portion clamped by the eyes of said bolts to said bar to serve as a reinforcement therefor, and having its extremities outturned substantially from 60 the surface of said bar, and truss rods having their inner ends secured to said outturned extremities of said member and having their outer ends fixed at the outer ends of said bar with provision for adjustment to 65 apply a tension thereto.

In testimony whereof, I have signed my name to this specification.

JAMES A. WALKER.
